UNITED STATES PATENT OFFICE

135,381

DESIGN FOR A CASE FOR SAFETY RAZORS AND SHAVING ACCESSORIES

Morton Hollis, Brookline, Mass., assignor to Gillette Safety Razor Company, Boston, Mass., a corporation of Delaware

Application January 29, 1943, Serial No. 109,360

Term of patent 14 years

To all whom it may concern:

Be it known that I, Morton Hollis, a citizen of the United States, residing at the town of Brookline, in the county of Norfolk and Commonwealth of Massachusetts, have invented a new, original, and ornamental Design for a Case for Safety Razors and Shaving Accessories, of which the following is a specification, reference being had to the accompanying drawing, forming part thereof, in which—

Fig. 1 is a view in perspective of a closed case for safety razors and shaving accessories showing my new design; and

Fig. 2 is a similar view of the case in opened position.

I claim:

The ornamental design for a case for safety razors and shaving accessories, as shown.

MORTON HOLLIS.
